UNITED STATES PATENT OFFICE

155,862

DESIGN FOR A COMBINATION RECORD PLAYER AND RADIO CABINET

Samuel E. Adler, Chicago, Ill.

Application October 9, 1948, Serial No. 149,061

Term of patent 14 years

(Cl. D56—4)

To all whom it may concern:

Be it known that I, Samuel E. Adler, a citizen of the United States, and resident of Chicago, in the county of Cook, State of Illinois, have invented a new, original, and ornamental Design for a Combination Record Player and Radio Cabinet, of which the following is a specification, reference being had to the accompanying drawings, forming a part thereof.

Fig. 1 is a front perspective view of a combination record player and radio cabinet showing my new design;

Fig. 2 is a view of the record player and radio cabinet in front elevation;

Fig. 3 shows the new design in side elevation when viewed from the right hand side of Fig. 2; and

Fig. 4 is a top plan view of the combination record player and radio cabinet.

I claim:

The ornamental design for a combination record player and radio cabinet, substantially as shown.

SAMUEL E. ADLER.
